US00D687038S

(12) **United States Design Patent**
Chatterjee et al.

(10) **Patent No.:** US D687,038 S
(45) **Date of Patent:** ** Jul. 30, 2013

(54) **DOCKING STATION FOR A COMPUTING DEVICE**

(71) Applicant: **Hewlett-Packard Development Company, L.P.**, Houston, TX (US)

(72) Inventors: **Manjirnath Chatterjee**, San Francisco, CA (US); **Yoshimichi Matsuoka**, Cupertino, CA (US); **Peter Cazalet**, Sunnyvale, CA (US); **William Justin Grange**, San Francisco, CA (US)

(73) Assignee: **Palm, Inc.**, Sunnyvale, CA (US)

(**) Term: **14 Years**

(21) Appl. No.: **29/443,146**

(22) Filed: **Jan. 14, 2013**

Related U.S. Application Data

(60) Division of application No. 29/402,095, filed on Sep. 20, 2011, now Pat. No. Des. 674,391, which is a continuation-in-part of application No. 12/620,478, filed on Nov. 17, 2009.

(51) **LOC (9) Cl.** 14-02

CLAIM

(57) The ornamental design for a docking station for a computing device, as shown and described.

DESCRIPTION

FIG. 1 is a perspective view of a docking station for a computing device;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines illustrate surface features and other features of the docking station and form no part of the claimed design.
